Primary Examiner — Cynthia R Underwood

(57) **CLAIM**

The ornamental design for a cord organizer, as shown and described.

DESCRIPTION

FIG. 1 is a front, top perspective view of a cord organizer, showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is another perspective view of the cord organizer, shown in an environment of use.

The broken lines of a kitchen appliance in FIG. 8 shown in the drawings depict environmental structure that form no part of the claimed design.

1 Claim, 8 Drawing Sheets
